William J. Stedman, Eau Claire, Wis., assignor to National Pressure Cooker Company, Eau
Claire, Wis., a corporation of Wisconsin

Application July 24, 1944, Serial No. 114,535

Term of patent 14 years

(Cl. D44—1)

To all whom it may concern:

Be it known that I, William J. Stedman, a citizen of the United States, residing at Eau Claire, in the county of Eau Claire and State of Wisconsin, have invented a new, original, and ornamental Design for Pressure Cooker or Similar Device, of which the following is a specification, reference being made to the accompanying drawing, forming a part thereof.

The figure is a perspective view of a pressure cooker showing my new design.

I claim:

The ornamental design for a pressure cooker or similar device, substantially as shown.

WILLIAM J. STEDMAN.
